UNITED STATES PATENT OFFICE.

ALBERT W. SCHLOSS, OF GROSSE POINTE SHORES, MICHIGAN.

SLEEVE.

1,096,270.

Specification of Letters Patent. Patented May 12, 1914.

Application filed November 4, 1912. Serial No. 729,210.

To all whom it may concern:

Be it known that I, ALBERT W. SCHLOSS, a citizen of the United States of America, residing at Grosse Pointe Shores, in the county 5 of Macomb and State of Michigan, have invented certain new and useful Improvements in Sleeves, of which the following is a specification, reference being had therein to the accompanying drawings.

10 In the use of outer garments and more particularly those worn by drivers of vehicles, and by others in outdoor pursuits it is desirable that means be provided for preventing entrance of air to the sleeve ends 15 and that any device for this purpose does not detract from the appearance of the garment when not in actual use.

This invention relates to sleeves for garments and to an arrangement thereof where- 20 by the portion which forms a finish when not in use may be brought into such position that it effectually closes the sleeve around the wrist of the wearer.

The invention consists in the matters here- 25 inafter set forth and more particularly pointed out in the appended claim.

In the drawings, Figure 1 is a view of a portion of a sleeve that embodies features of the invention showing a cuff in open position 30 with one corner turned back to illustrate the fastening means; Fig. 2 is a view of the reverse side of the sleeve showing the other corner of the cuff in open position; Fig. 3 is a view showing the cuff extended and par- 35 tially fastened, the margin of the sleeve being cut away to give clear view; Fig. 4 is a view of the reverse side that corresponds to Fig. 2 and shows the cuff in closed posi- 40 tion; and Fig. 5 is a view in section taken on or about line V—V of Fig. 3.

As shown in the drawings, a sleeve 1 of suitable material and pattern has a cuff 2 whose upper marginal portion 3 is suitably stitched or otherwise attached permanently 45 within the sleeve at an interval from the outer margin of the latter and preferably at the inner edge of the hem 4 thereof. The cuff is of smaller diameter than the sleeve and has one end margin 5 near which an 50 inner button 6 and an outer button 7 are

applied. The other margin 8 of the cuff is arranged to overlap the margin 5 and is pro- 55 vided with a buttonhole indicated at 9 to engage the button 6 and another one indicated at 10 to engage the button 7. Thus when the cuff is extended as indicated in Figs. 3, 4 and 5 it may be snugly drawn around the wrist of the wearer and buttoned in such manner as to effectively close the sleeve. The cuff is also arranged to fall back 60 when not in use and when so disposed the buttonhole 10 is arranged to engage a finish- 65 ing button 11 such as is usually applied to a coat sleeve for ornament. The other corner of the cuff on which the button 7 is fastened has a hook 13 or like fastening means adapt- 70 ed to engage a complementary loop or eye 14 or the like. In applying the cuff to the inside of the sleeve the sleeve lining indicated at 15 may be stitched over the cuff which is 75 preferably folded on itself to form an inner facing 16 so that the outside of the cuff when it is folded back will correspond to the body of the sleeve if desired. As a result of this construction a coat sleeve is obtained which 80 presents a neat and attractive appearance when in ordinary use and which when the cuff is extended, is effectively closed around the wrist of the wearer and is therefore of special advantage for outdoor use and for 85 driving or riding in the open.

Obviously, changes in the details of construction may be made without departing from the spirit of the invention and I do not care to limit myself to any particular form 85 or arrangement shown.

What I claim is:—

The combination with a garment sleeve, of a reversible cuff of less diameter than said sleeve, said cuff having the inner end there- 90 of secured in said sleeve between said sleeve and the lining thereof whereby the outer end of said cuff can be folded against the outer side of said sleeve, said cuff having separable ends, a button carried by one end 95 of said cuff, said cuff having the opposite end thereof provided with a buttonhole adapted to receive said button and retain said cuff in a closed extended position relatively to said sleeve, a button carried by the outer 100

side of said sleeve and adapted to engage the button of said cuff, a hook carried by said cuff adjacent to the button thereof, and an eye carried by the outer side of said sleeve and adapted to receive said hook, said hook and eye being concealed by said cuff and co-operating with the button of said sleeve and the buttonhole of said cuff in retaining said

cuff folded against the outer side of said sleeve.

In testimony whereof I affix my signature in presence of two witnesses.

ALBERT W. SCHLOSS.
